UNITED STATES PATENT OFFICE.

FRED EDWIN SEAL, OF WINCHESTER, VIRGINIA.

TOY CAR.

1,108,628.

Specification of Letters Patent.

Patented Aug. 25, 1914.

Application filed April 21, 1914. Serial No. 833,438.

To all whom it may concern:

Be it known that I, FRED E. SEAL, a citizen of the United States, and a resident of Winchester, in the county of Frederick and State of Virginia, have made an Improvement in Toy Cars, of which the following is a specification.

My invention is a toy car having internal grooved wheels adapted to run on a single cord, wire, or rail, and whose center of gravity is below such wheels, so that the car is self-supported.

The invention is characterized by certain novel and advantageous features of construction, arrangement, and combination of parts, as hereinafter described.

In reference to the accompanying drawings: Figure 1 is a longitudinal section on the line 1-1 of Fig. 3, showing the car mounted upon a wire. Fig. 2 is a horizontal section on the line 2-2 of Fig. 1. Fig. 3 is a vertical cross-section on the line 3-3 of Fig. 1. Fig. 4 is a plan view of the sheet metal blank from which the body of the car is formed. Fig. 5 is a perspective view of a portion of the car body.

For the sake of lightness and economy in manufacture, the body of the car is formed of a sheet metal blank A, Fig. 4, the same being oblong and rectangular and provided on one side with end extensions *a*. The blank is bent or doubled upon itself into the form shown in Figs. 3 and 5, the main portions of the sides being parallel and provided with a series of openings which simulate windows.

The lower portions of edges *b* of the blank form downward extensions which are bent inward or inclined toward each other at a considerable angle, but whose lower ends are separated, as shown in Fig. 3, by a space sufficient to receive the wire *x* upon which the car runs. When the sides of the body have been bent into the form described, the end extensions *a* are bent laterally or at right angles to the axis of the body so as to form the ends of the car body, and they are conveniently secured by means of claws *c* which are formed integrally with the extension *a* and enter slots provided in the adjacent side of the car body, as shown in Fig. 5.

Near each end of the car body is located a transverse axle *d* having its bearings in the sides of the body just above the inclines

b, and upon the center of such axle is mounted a grooved wheel *e* which runs on a wire, cord, or rail *x* as shown. Upon the same axle *d* are mounted two wheels *f* whose function is practically to add momentum to the car and thus assist the latter in running rapidly and steadily when due impetus has been given to it in any suitable manner.

In order to bring the center of gravity below the running wheels *e*, the car body is weighted, as indicated at *g*. My preferred method for providing weights at this point is to curve the lower inclined portions *b* of the car body, as shown in Figs. 1, 3, 5, thus forming receptacles for weights proper. These may consist of lead laid into the grooved receptacles and which will be held therein by slight compression of the latter. I prefer, however, as a rule, to run hot lead into the receptacles provided in the manner described. It is obvious that the center of gravity may be raised or lowered by placing the weights higher or lower.

To enable the car body to be easily placed upon a wire or other support, or, in other words, to guide the wire into the grooves of the wheels *b*, I provide guides *h* which are in the nature of wires or metal strips secured to the lower edges of the inclines *b* and extending upward into close proximity to the wheels *e*, as shown clearly in Fig. 3. These guides enable the wheels of the car body to be placed on the wire with great facility. In practice, the lower edges of the guides *h* may be inserted in the grooves or pockets formed for reception of the weights *g*, and in fact they may be secured therein by clasping them about the weight or by inserting them in place under the hot lead as poured in, so that as the latter cools the guides will be held rigidly in due position.

By the construction and combination of parts described, I produce a car distinguished by lightness, cheapness, and facility of application to, and removal from, a wire or other support and adapted to be propelled with ease and rapidity.

The car body may be operated, that is to say, driven on a single wire, cord, or rail in various ways, that is to say, in rails which have been heretofore employed. For instance, the wire may be raised or depressed at one end to place it in inclined position; or the car may be provided with a spring-actuated gearing for propelling it.

I claim:—

1. A car body formed of a sheet of thin flexible material which is bent or doubled along its transverse middle, the sides of the same being in parallel position and the lower edges of the sides bent inward at a considerable angle and their terminals or lower edges spaced apart to permit the application of a car to, and removal of the same from, a wire or other support.
2. A sheet metal car-body having internal running wheels, and its lower edges extended downward and curved at their extremi-

ties to produce pockets, and weights inserted and held in said pockets, the same being spaced apart, as described. 15

3. A toy car comprising a body having transverse axles near its end and running wheels mounted fast thereon, central momentum wheels also mounted on the same 20 axles and arranged in pairs and on opposite sides of the running wheels, as described.
